AUTOMATIC PARAFFIN CUTTER

William A. Gould, Hobbs, N. Mex.

Application June 17, 1946, Serial No. 677,229

9 Claims. (Cl. 166—18)

1. This invention relates to improvements in automatic paraffin cutters for oil and gas wells.

An object of the invention is to provide an improved reciprocating and rotating automatically operated paraffin cutter for oil and gas wells.

Another object of the invention is to provide an improved reciprocating and rotating automatically operated paraffin cutter and brush for cleaning the inside walls of the well casing in an oil well or gas well.

A further object of the invention is to provide an improved reciprocating and rotating automatically operated paraffin cutter and brush and an interconnected choke for cleaning the inside surface of an oil or gas well casing.

A still further object of the invention is to provide an improved automatic paraffin cutter for oil and gas wells which will be highly efficient in use and relatively inexpensive to manufacture and produce.

Further objects will appear as the description proceeds.

In the accompanying drawings which form a part of this application,

Figure 1 is a vertical sectional view through an oil or gas well casing showing the improved automatic paraffin cutter in position therein;

Figure 2 is a transverse sectional view taken on the line 2—2 of Figure 1;

Figure 3 is a transverse sectional view taken on the line 3—3 of Figure 1;

Figure 4 is a transverse sectional view taken on the line 4—4 of Figure 1, and

Figure 5 is a vertical sectional view taken on the line 5—5 of Figure 1.

Like characters of reference are used throughout the following specification and the accompanying drawings to designate corresponding parts.

In carrying out the invention, there is provided an oil or gas well casing shown as having interconnected threaded casing or pipe sections 1, 2 and 3. Annularly disposed stop flanges 4 and 5 are formed adjacent the ends of the casing sections 1 and 3, the purpose of which will be herein-after described.

A sectional rod or tube generally denoted by the reference numeral 6 is composed of a plurality of sections having internally threaded end sockets 7 adapted to receive the adjacent threaded pipe or tube end 8.

A transversely extending stop arm or bracket 9 is secured to the rod 6 adjacent its upper end, and is adapted to engage the interiorly disposed annular stop flange 4 in the upper end of the casing 1.

2. A wire brush 10 is mounted loosely about the rod 6 for spiral as well as rotary movement and engages or contacts the inner surface of the well casing to clean the same in a manner to be described.

3. Slidably disposed on the rod 6 below the brush 10 is a cutter blade 11 having a supporting web 12 and somewhat resilient cutting edges 13 and 14 for cutting the paraffin from the inner surface 10 of the well casing as the device automatically rotates and reciprocates upwardly and downwardly within the well casing.

4. The upward and downward movement of the cutter 11 on the rod 6 is limited by the enlargements 15 and 16 on the said rod 6.

5. A tubular housing 17 is slidably received in the well casing adjacent the lower end of the rod 6, and is reduced or swaged down to provide the lower end housing portion 18 through which the vertically arranged oppositely disposed slots 19 and 20 are formed.

6. A cross rod or pin 21 is slidably received within and extends through the housing 18 between said slots 19 and 20, and functions as a pintle for the spaced hinges 22 and 23, which in turn are connected with the semi-circular damper or choke plates 24 and 25. The cross rod is thus secured to the plates but, of course, other securing means may be utilized.

7. The lower end of the rod 6 is formed with the oppositely disposed spring fingers 26 and 27, whose lower extremities are hinged at their inner surfaces as at 28 and 29 to the center of the straight edges of said choke plates 24 and 25.

8. The opposite ends of the rod or pin 21 not only extend through the opposite slots 19 and 20, but extend outwardly therebeyond so as to be engaged by the annularly disposed stop flange 5 on the lower section 3 of the well casing.

9. From the foregoing description it will be apparent that the mode of operation will be as follows:

10. When the automatic paraffin cutter is in position within the well casing, its action will be an automatic rotary and reciprocating one, held within the limits of the stop flanges 4 and 5 formed in the well casing.

11. It is to be noted that the stop flanges 4 and 5 in the well tubing or casing function to limit the reciprocating movement of the rod 6 received therein. The movement of the rod upwardly is limited by the engagement of the stop flange 4 with the stop arm or bracket 9 which is transversely secured to the rod adjacent its upper end.

12. The sleeve 17, which receives the opposing ends of the rod 21, serves as a weighted guide sleeve

for the rod, so that the weight of the sleeve on the rod or pin tends to extend or unfold the plates 24 and 25 and urges them toward a bore closing position transverse in the tubing. Thus, the weight of the sleeve, when the pin rests on the lower stop 5, as the entire rod and components thereof drop downwardly in the tubing, tends to force the rod 21 outwardly and spread the spring fingers 26 and 27. The plates 24 and 25 are thus unfolded about the hinges 28 and 29 and move about the pivot pin or rod 21.

With the plates disposed in a bore closing position, transverse to the spring fingers, the upward flow of fluid pressure from the well will impinge on the choke plates and cause the tube 6 and its components to move upwardly in the tubing. As the rod moves upwardly, the brush and cutter will rotate on the rod. The force of the fluid pressure will be centralized substantially at the middle of the choke plates and will force the straight edges of the choke plates upwardly in towards the upper space formed by the spring fingers 26 and 27. The fingers being in an expanded position, when the rod begins its upward movement, will receive the force of the fluid pressure and the force of the fluid pressure at the central point of the plates coupled with the resilient contractability of the fingers, will force the plates to buckle or move upwardly to a closed position within the spring fingers.

From the foregoing description, it will be apparent that there has been devised a highly efficient form of automatic paraffin cutting device for oil and gas wells which will be relatively inexpensive to manufacture and operate.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. An automatic paraffin cutter for use in an oil well flow tubing comprising an elongated rod having a resilient bifurcated lower end, a brush and cutter carried by the rod, a pair of hingedly connected plates pivotally secured to the ends of the branches of the bifurcated end and movable inwardly thereof to a folded position and outwardly to an extended position thereon, a guide sleeve embracing said end and plates, said sleeve having diametrically opposing slots, a cross bar slidably disposed in said slots and connected to the hinged edges of the plates, and stop means on the interior of the flow tubing for limiting the upward and downward movement of the rod.

2. An automatic paraffin cutter for use in an oil well flow tubing comprising an elongated rod having parallel spring fingers formed on its lower end, a brush and cutter mounted on the rod, a pair of hingedly connected plates pivotally secured to the ends of the fingers at the inner surfaces thereof, said plates being movable to an extended position transversely of the fingers and to a folded position within the fingers, a cross rod connected to said plates and a sleeve embracing said plates and having opposed slots therein receiving the ends of the cross rod.

3. An automatic paraffin cutter assembly for use in an oil well flow tubing comprising an elongated rod having a cutter and brush mounted thereon, spring fingers formed at the lower end

of the rod, means pivotally carried by the fingers for raising the rod in the tubing responsive to the fluid pressure, said means being movable on the fingers to bore opening and bore closing positions, a cross rod connected to said means and a guide sleeve for said rod.

4. In an automatic paraffin cutter assembly for use in an oil well flow tubing, an elongated rod received in said tubing, spring fingers formed on the lower end of the rod, a pair of hingedly connected plates pivotally affixed to the ends of the fingers at their inner surfaces, means connected to said plates for moving the plates outwardly of the fingers to a bore closing position upon downward movement of the rod, said plates being positionable thereby transversely of the fingers and reactive to the fluid pressure in the tubing for raising the rod.

5. In an automatic paraffin cutter assembly for use in an oil well flow tubing, an elongated rod received in said tubing, spring fingers formed on the lower end of the rod, a pair of hingedly connected plates pivotally affixed to the ends of the fingers at their inner surfaces, means operatively connected to said plates for moving the plates outwardly of the fingers upon downward movement of the rod, said plates being positionable thereby transversely of the fingers and reactive to the fluid pressure in the tubing for raising the rod, said last means including a cross rod connected to the hinged edges of the plates and a sleeve embracing said plates and having slots therein for slidably receiving the opposing ends of the rod.

6. In an automatic paraffin cutter assembly for use in an oil well flow tubing, an elongated rod received in said tubing, spring fingers formed on the lower end of the rod, a pair of hingedly connected plates pivotally affixed to the ends of the fingers at their inner surfaces, means operatively connected to said plates for moving the plates outwardly of the fingers upon downward movement of the rod, said plates being positionable thereby transversely of the fingers closing the tubing bore and reactive to the fluid pressure in the tubing for raising the rod, said means including a cross rod connected to the hinged edges of the plates and a sleeve embracing said plates and having slots therein slidably receiving the opposing ends of the rod, stop means on the interior of the flow tubing for limiting the downward movement of the sleeve and elongated rod.

7. In an automatic paraffin cutter assembly for use in an oil well flow tubing, an elongated rod received in said tubing, spring fingers formed on the lower end of the rod, a pair of hingedly connected plates pivotally affixed to the ends of the fingers at their inner surfaces, means operatively connected to said plates for moving the plates outwardly of the fingers upon downward movement of the rod, said plates being positionable thereby transversely of the fingers closing the tubing bore and reactive to the fluid pressure in the tubing for raising the rod, said last means including a cross rod connected to the hinged edges of the plates and a sleeve embracing said plates and having slots therein slidably receiving the opposing ends of the cross rod, stop means on the interior of the flow tubing for limiting the upward and downward movement of the elongated rod.

8. In an automatic paraffin cutter assembly for use in an oil well flow tubing, an elongated rod, spring fingers on the lower end of the rod, a pair of semi-circular plates hingedly secured

together at their straight edges, means for pivotally affixing the hinged edges of the plates to the inner surfaces of the ends of the fingers, said plates being movable inwardly of and outwardly of the fingers into bore opening and bore closing positions, respectively, a cross rod secured to the straight edges of the plates, a sleeve embracing said plates and having slots receiving the ends of the cross rod, said cross rod being moved downwardly by the sleeve to urge the plates outwardly of the fingers, stop means for limiting the downward movement of the sleeve and rod and stop means on the interior of the flow tubing for limiting the upward movement of the rod, said rod being moved upwardly by fluid pressure acting upwardly against the plates when in a tubing bore closing position.

9. In an automatic paraffin cutter for use in an oil well tubing, an elongated rod having a cutter and brush mounted thereon, spring fingers formed on the lower end of the rod, a pair of hingedly connected actuating plates pivotally secured to the ends of the fingers at their inner surfaces, means embracing the plates for urging said plates outwardly of the fingers into an expanded or bore

10
